UNITED STATES PATENT OFFICE.

MICHAEL PETRIE, OF IRVINGTON, NEW JERSEY.

SUPPORTING ATTACHMENT FOR IRONING-BOARDS, TABLES, BENCHES, AND THE LIKE.

1,133,662.

Specification of Letters Patent. Patented Mar. 30, 1915.

Application filed May 22, 1914. Serial No. 840,152.

To all whom it may concern:

Be it known that I, MICHAEL PETRIE, a citizen of the United States, residing at Irvington, in the county of Essex and State 5 of New Jersey, have invented certain new and useful Improvements in Supporting Attachments for Ironing-Boards, Tables, Benches, and the like; and I do hereby declare the following to be a full, clear, and 10 exact description of the invention, such as will enable others skilled in the art to which it appertains to make and use the same, reference being had to the accompanying drawings, and to characters of reference 15 marked thereon, which form a part of this specification.

This invention has reference, generally, to improvements in supporting attachments for ironing boards, tables, benches, and the 20 like; and, the present invention relates, more particularly, to a novel and simply-constructed folding support for ironing boards, tables, benches, and the like, which is adapted to be easily and quickly attached 25 to the board, table, or bench, and is readily brought into its folded relation against the back of the ironing board, table or bench, or can be readily brought into a rigid supporting relation therewith.

30 The invention has for its principal object to provide a novel, simple, and easily operated foldable support for ironing boards, tables, benches, and the like, which is readily attached and is of the general character 35 hereinafter more particularly set forth.

Other objects of this invention not at 40 this time more particularly enumerated will be clearly understood from the following detailed description of the present invention.

With the various objects of the present invention in view, the invention consists, primarily, in the novel foldable support for 45 ironing boards, tables, benches, and the like; and, the invention consists, furthermore, in the novel arrangements and combinations of the devices and parts comprising the support, as well as in the details of the construction of the same, all of which 50 will be more fully described in the following specification, and then finally embodied in the clauses of the claim which are appended to and which form an essential part of this specification.

The invention is clearly illustrated in the 55 accompanying drawings, in which:—

Figure 1 is a side elevation of an ironing board and a foldable support attached thereto, showing one embodiment of the principles of the present invention; and 60 Fig. 2 is an end view of the same, looking in the direction of the arrow *x* in said Fig. 1. Fig. 3 is a plan view of a portion of the back of the ironing board and the support, the latter being shown folded against the 65 back of the board, and said view being made on an enlarged scale. Fig. 4 is a fragmentary view, partly in side elevation and partly in vertical section, said section being represented as being taken on line 70 4—4 in Fig. 2 of the drawing, looking in the direction of the arrow *y*, showing a spring-latch in its holding engagement with a hinge-plate, for the rigid supporting relation of a support or leg to said hinge-plate; 75 and Fig. 5 is a similar view of the same parts represented in said Fig. 4, but showing the spring-latch withdrawn from its holding relation with the hinge-plate, to permit the support or leg to be swung into 80 its folded position against the back of the ironing board, table, or bench. Fig. 6 is a side elevation of a table and a pair of foldable supports; and Fig. 7 is an end elevation 85 illustrating a slightly modified arrangement of the principles of the present invention, but still embodying the principles of the same.

Similar characters of reference are employed in the said above described views, to 90 indicate corresponding parts.

Referring now to the said drawings, the reference-character 1 in Figs. 1, 2, 3, 4, 5 and 7 indicates the usual ironing board, and in Fig. 6 the reference character 2 indicates 95 a suitable table or bench-top, to either of which may be attached a folding support or supports of the general character to be presently more fully described. This support consists, essentially, of a suitably shaped 100 plate-like element, as 3, the main portions of which are angularly bent in opposite directions, as at 4 and 5, see more particularly Fig. 2 of the drawings, and each bent part 4 and 5 having a still further bent portion, 105 as 6, said portions 6 terminating in perforated ears 7, for the attachment of the said plate-like element, by means of screws 8, or

other suitable fastening means upon the back of the ironing board 1, or the table or bench-top 2, substantially in the manner shown in the several figures of the drawings. 5 Thus, it will be seen, that on account of the shape of the said plate-like element 3 with the bottom of the board 1 or the table-top or bench 2, a suitable open space 9 is provided, the purpose of which will be self-evident from an inspection of Figs. 4 and 5 10 of the drawings. The angular main portions 4 and 5 are each provided along one of their marginal edges with suitably formed pintle-receiving ears 10 to which are pivotally connected, by means of pintles 11, the pintle-receiving ears 13 of hinge-plates 12. Each hinge-plate 12 is suitably secured by means of screws 14, or other suitable fastening means, to the upper end-portions of 20 suitable supports or legs 15, in such a manner that the upper end-surfaces 16 of the said supports or legs 15, when moved into their supporting relation with the plate-like member 3, will rest directly upon the lower 25 surfaces of the angular main portions 4 and 5, so that the said legs 15 will naturally assume an outwardly spread-apart relation, shown in Fig. 2 of the drawings. Upon the face-portions of the said legs 15 opposite the 30 face-portions upon which the hinge-plates 12 are secured, are suitably fastened by means of screws 17, or other suitable fastening means, suitably-formed spring-plates or bars, as 18, each plate or bar 18 having upon 35 its upper portion a latch-dog 19, formed with an engaging member or nosing, as 20, adapted to be sprung into latched holding engagement with the upper surfaces of the 40 portions 4 and 5, as shown in Figs. 1, 2 and 4 of the drawings, and each latch-dog 19 being provided with a suitable pull-knob or finger-piece, as 21, for the disengagement of 45 the latch-dogs from the portions 4 and 5 of the plate-like element 3 as shown in Fig. 5 of the drawings, and to permit of the folded arrangement of the legs 15 against the 50 back of the ironing board, table or bench, in the manner represented in Fig. 3 of the drawings. 55 When the herein-above described support is to be used with an ironing board, but one support is attached to the board 1 near one end thereof, as shown in Fig. 1, but when employed for the supports of a table or 60 bench, then a support is attached near the respective ends of the board 2, in the manner represented in Fig. 6 of the drawings. 65 In lieu of a single plate-like element 3, two separate elements 22 may be employed, as clearly indicated in Fig. 7 of the drawings. In that case, the respective plate-like elements 22 are each provided with oppositely extending angular portions 23, and the bent portions 24 provided with the per- 66 forated ears 25 and screws 26, or other suit-

able fastening means, for securing said elements 22 to the back of an ironing board, table or bench, substantially in the manner represented in said Fig. 7. Each portion 23 is provided with pintle-receiving ears 70 with which are pivotally connected in the manner hereinabove described, the legs 15 which are provided with the spring-plates or bars 18 and the latch-dogs 19, which co-operate with the portions 23 of the elements 75 22 in the same manner and for the same purposes herein-before described in connection with the construction illustrated in Figs. 1 to 6 inclusive.

The manipulation of the support or supports for bringing the same into supporting relation, or for folding the same, will be clearly understood from the foregoing description and from an inspection of the several figures of the drawings, and need not, 85 therefore, be further described.

I am aware, that some changes may be made in the general arrangements and combinations of the various devices and parts, as well as in the details of the construction 90 of the said parts, without departing from the scope of the present invention as described in the foregoing specification, and as defined in the clauses of the claim which are appended to the said specification. Hence, 95 I do not limit my present invention to the exact arrangements and combinations of the various devices and parts as described in the said specification, nor do I confine myself to the exact details of the construction of the 100 said parts as illustrated in the accompanying drawings.

I claim:—

1. A support for ironing boards, tables or benches, comprising a plate-like element 105 adapted to be attached to and having its main body spaced away from the back of the ironing board, table or bench, a hinge-member pivotally connected with said main body of said plate-like element, a leg to 110 which said hinge-member is secured, a spring-latch also secured to said leg, said spring-latch having an engaging member adapted to be sprung into separable holding 115 engagement with the upper surface of said main body of said plate-like element when said leg is moved into its supporting or operative position.

2. A support for ironing boards, tables or 120 benches, comprising a plate-like element adapted to be attached to the back of the ironing board, table or bench, said plate-like element being provided with angularly bent members forming with the back of the ironing board, table or bench a receiving space, 125 a hinge-member pivotally connected with each angularly bent member, a leg connected with each hinge-member, and a spring-latch also secured to each leg, said spring-latch having an engaging member adapted to be 130

sprung into said receiving space and over an angularly bent member in separable holding engagement therewith when said legs are moved into supporting or operative positions, and means for retracting said spring-latches.

3. A support for ironing boards, tables or benches, comprising a plate-like element adapted to be attached to the back of the ironing board, table or bench, said plate-like element having its main portion angularly bent in opposite directions, each angularly bent portion being provided with another bent portion, all arranged to form with the back of the ironing board, table or bench a receiving space, and perforated fastening ears extending outwardly from said last-mentioned bent portions, pintle-receiving members extending from the said

first-mentioned angularly bent members of 20 the plate-like element, pintles mounted in said pintle-receiving members, a hinge-member pivotally connected with each pintle, supporting legs to which said hinge-members are secured, and a spring-latch also secured to each leg, said spring-latches having engaging members adapted to be sprung into said receiving space and in separable holding engagement with the said first-mentioned angularly bent members of the said 30 plate-like element.

In testimony, that I claim the invention set forth above I have hereunto set my hand this 19th day of May, 1914.

MICHAEL PETRIE.
